UNDERGARMENT CONSTRUCTION

Ida Combs, Philadelphia, Pa.

Application June 8, 1946, Serial No. 675,427

2 Claims. (Cl. 2—43)

1

My invention relates to women's clothing and particularly to undergarments worn about the hips.

I have found that women prefer for several reasons to wear a girdle or a panty girdle which incorporates a crotch member extending front to back between the legs.

Primarily, the crotch piece is used to prevent the garment from being displaced on the hips of the wearer during usage. This feature is especially important when a foundation garment of the elastic or supporting type is used. Another reason for the desirability of a crotch piece is to provide suitable covering for the crotch, thereby avoiding embarrassment and the necessity for wearing a separate garment.

Heretofore, garments of this type have been frequently held in place solely by means of garters which are attached to stockings. However, it has been found that this practice is unsatisfactory because the garters themselves frequently become unfastened or the pull of the garters causes the stockings to tear thus becoming completely ruined by "runners." In addition, many women prefer to wear no stockings at all particularly in warmer climates and in the summer. This means that the garters must be removed from the garments to avoid discomfort and also the anchorage afforded by the stockings and garters is lost.

In view of the above-mentioned reasons for incorporating a crotch on any such type of garment, whether it be completely elastic, partially elastic or fully inelastic, certain requirements for a crotch piece will become apparent.

First, the crotch member itself must be of a shape causing no discomfort to the wearer. Second, the entire garment or at least the crotch piece must be able to withstand frequent and probably daily laundering. Third, where the crotch member is applied to garments other than the fully elastic type, which are not readily slipped up or down over the thighs, the crotch piece should be capable of quick and convenient detachment to enable the wearer to perform the necessary functions of elimination. Fourth, the fastening devices for the crotch must provide absolute security against accidental detachment and at the same time not cause discomfort to the wearer. Fifth, the crotch member itself as well as the fastening devices must not be noticeable under a tight fitting dress. Therefore, I have provided a crotch member for use on any type of garment which fulfills the above requirements.

2

I am familiar with previous attempts to solve this problem and I realize that some of the prior art devices have been helpful in proposing a partial solution. Examples of such prior art are the patents to Elterich 872,172; Miller et al. 2,070,515, Blair 2,246,714, Clark 2,320,408, and Blair 2,397,641.

The expedient of using a detachable crotch piece is clearly disclosed in one or more of the foregoing patents; nevertheless, the object of my invention is to provide a detachable crotch construction which fulfills each of the above requirements. Therefore, I have constructed a garment with a detachable crotch member combined with a detachable insert which can be easily removed for laundering. Furthermore, an object of my invention is to provide fasteners for the crotch piece and the insert which cannot become accidentally detached regardless of age or amount of use of the garment and which will be comfortable and unnoticeable.

Many garments of this character cannot be frequently laundered without materially decreasing their life and impairing whatever elastic supporting function the garment may have. It, therefore, becomes important that the crotch member be capable of much more frequent laundering than the entire garment and my construction takes care of this necessity with a minimum of inconvenience.

My construction contemplates an inexpensive insert which may be completely disposable so that new inserts may be added if it is not desired to launder the insert separately. Furthermore, I have provided a detachable fastener for the crotch and insert which is inexpensive to manufacture but which will not become accidentally disengaged regardless of the posture or activities of the wearer. In addition, I incorporate a method of securing the fasteners which prevents them from chafing the wearer and which also insures that the crotch is held in proper position at all times.

Further objects will be apparent from the specification and drawings, in which:

Fig. 1 is a front elevation of my improved girdle partly cut away and showing the crotch piece in open position;

Fig. 2 is a section taken along lines 2—2 of Fig. 1;

Fig. 3 is a sectional view showing the method of attaching and protecting the loops on the crotch piece and the trunk of the garment;

Fig. 4 is an enlarged detail showing a preliminary step in fabricating the loops;

Fig. 5 is an enlarged detail view of the fastener with the fastener loop sewed to the detachable crotch piece; and

Fig. 6 is an enlarged sectional view taken along lines 6—6 of Fig 1.

While certain novel features of the invention are disclosed herein with considerable detail with respect to certain particular forms of the invention, it is not desired to be limited to such details since many changes and modifications may well be made without departure from the spirit of invention in its broadest aspect.

Referring now to the drawings, panty girdle 10 illustrates the type of garment to which my invention is particularly adapted because in the true girdle, which is an elastic supporter, there is no crotch member at all and the girdle is held in position on the wearer by means of garters attached to the girdle itself. Such a garment, it will be understood, does not require the frequent laundering that any crotched garment will need. Where, however, the garment requires additional means for preventing its retention of position on the wearer and particularly in heavier and older people, it is very desirable to have a crotch member attached to the garment which may be used either in place of garters or in addition to them.

Therefore, I have illustrated my improvement in connection with such a garment which is known to the trade as a "panty girdle."

The girdle itself, as mentioned above, is comprised of an elastic or semi-elastic material designed to fit the wearer tightly. The crotch member 11 is, however, made of an inelastic material and has attached thereto a plurality of fasteners 12 along its front extremity. Fasteners 12 engage in loops 13 which are secured in a manner to be described more particularly hereinafter to the front portion of the panty girdle and are completely enclosed by strips of material 14 and 15 (Fig. 3). Crotch piece 11, as shown in Fig. 1, is permanently attached to the back of girdle 10 at 16 by means of stitches 17. The seam at 16 is reinforced by additional tapes 18 (Fig. 6). If desired, however, I contemplate that the crotch may be made completely detachable at the back in the same manner as is shown in Fig. 1 at the front. For most purposes, however, it will be preferable to insure that the crotch piece is at all times permanently attached to the body of the panty girdle since the detachment at the front of the girdle provides ample means for opening the crotch when necessary.

Attached to the upper side of crotch piece 11 is a removable insert 19 of a generally square or diamond shape. A fastener 12 is secured to each corner of insert 19 and these four fasteners are inserted through and held in place by loops 20. I have found that a square or diamond shape, as illustrated, is easily fabricated and is less likely to cause uncomfortable wrinkles than any other shape for the insert. For the purpose of clear illustration, I have shown loop 20 as being spaced from inside tape 18 but it may be found desirable to fabricate the garment so that the loop 20' is attached by means of stitches 17 instead of independently as shown. Also, for the purposes of clarity, I have illustrated fasteners 12 for the insert as extending outwardly from the insert itself. In actual fabrication, however, the fasteners on the insert would be attached underneath the insert in order that the edge of the insert will afford protection between the fastener and the body of the wearer. Where it is desired

to have the crotch 11 detachable at both ends, loop 20' will, of course, be attached to the crotch as shown in Fig. 1. Inserts 19 may be completely made of a fabric material or it is contemplated that a quantity of extra inserts will be supplied with each garment. In this event, it will be desirable that some of the inserts 19 be of rubberized material or partly rubber and partly fabric.

Crotch piece 11 has been described as being of an inelastic material but this term is used in comparison to the rubberized elastic material from which girdles are customarily made. Where, for invalids or for specialized applications, daily laundering of the crotch piece 11 is not necessary, it may be desirable to use a relatively more elastic material or elastically woven material for the sake of comfort.

Referring now to Fig. 4, the method which I employ to sew loops 13, 20, 20' and also all the loops 21 attaching fasteners 12 is to place the flat material between the main portion of the girdle, crotch, or insert, then reinforcing strip of material 22 is sewed through the loop member 21 and the fabric 23. A second seam is made at 24 as close to the edge of material 23 as possible. The tape or loop piece 21 is then inserted through the fastener 12, doubled back upon itself under the edge of piece 22 after which another seam 25 is made through all four thicknesses of material as shown clearly in Fig. 5. The identical method of forming the loops 13 is illustrated in Fig. 3 except that the fastener is not employed. The bight of the loop, however, is stitched securely to the enclosing material at 26. This method facilitates engaging and disengaging the fasteners; also, it prevents relative movement of the material attached by the fasteners, thus increasing the comfort of the entire garment.

The shape and manner of locking the attaching loops 20 to the garment are important from the standpoint of comfort. Crotch member 11 should be wide enough to avoid uncomfortable bunching of the member in the crotch of the wearer. The importance of this feature is appreciated when the purpose of the crotch member is kept in mind, namely, to prevent the garment from riding up on the hips of the wearer. By arranging loops 20 arcuately around the front of the trunk portion of the garment, undesirable gathering of crotch member 11 will be avoided.

The fasteners proper designated by the numeral 12 have a slotted opening at 27 through which they are attached permanently by tapes 21, as described above, and in addition the fasteners have a flat bar 28 extending beyond and parallel to the slot 27. Bar 28 terminates in a pointed section 29 which extends inwardly, partially covering the opening for slot 30 and aiding in preventing accidental disengagement of loop 13. Prong 31 located about midway of slot 30 also tends to retain the loop in slot 30. Similar fasteners have been used for other purposes but I have found that although many varieties of fasteners have been used to attach crotch members, this the only type which has proved satisfactory. The fasteners are very thin, cheap to manufacture, are easily and securely attached, and should be made of metal or of a synthetic plastic material for cheapness of fabrication and also to avoid corrosion.

While I have preferred to illustrate and describe my crotch construction as adapted to a foundation garment or girdle because its use on this type of garment will be more wide-spread,

it will be understood that the crotch construction is peculiarly adapted for specialized garments such as surgical corsets used by invalids and maternity cases. These garments are usually expensive and made-to-order; therefore, it is unlikely that a sufficient number is owned by any one individual to permit frequent laundering, and the addition of my crotch member to such a garment would eliminate the necessity of applying garters thereto.

Another type of garment which likewise cannot be frequently laundered without damage to the garment itself would be woolen underwear. A crotch member in accordance with my invention utilized on such a garment would prove to be not only more comfortable but would also increase the life of the garment, because in practice the crotch piece of any garment is the first part which wears out. It, therefore, would be only necessary to replace either the insert or the crotch piece itself.

Having thus described my invention, I claim:

1. In an undergarment of the panty girdle type having an elastic trunk portion, an elastic crotch stitched to the lower rear edge of the trunk portion, a plurality of fabric loops stitched arcuately around the lower front edge of the trunk portion, a plurality of hook fasteners attached to the front edge of the crotch and adapted to engage the loops, a washable fabric insert adapted to be secured to the elastic crotch, a plurality of fabric loops on said crotch, a plurality of hook fasteners on the insert adapted

to be secured in said last-mentioned loops to retain the insert in position on the crotch, a length of fabric material stitched on the inside of the trunk portion, and a corresponding length of fabric material stitched to the outside of the front portion, said fabric length adapted to overlie and enclose the fasteners for the crotch and trunk.

2. A panty girdle constructed in accordance with claim 1, in which the hook fasteners are attached to the crotch by means of fabric loops, one end of each fabric loop being stitched to the crotch between said crotch and an overlying horizontal fabric strip, a second row of stitches for said loop and the crotch in spaced relation to the first row, and a third row of stitches adapted to bind the fabric strip, the other end of the loop, the first length of the loop, and the crotch.
